WALL BLOCK

Raymond W. Clanton, 9735 Orcas Ave., Sunland, Calif.

Filed Nov. 4, 1963, Ser. No. 77,282

Term of patent 14 years

(Cl. D18—2)

FIG. 2

FIG. 3

FIG. 1 is an isometric view of a wall block showing my new design;

FIG. 2 is a front elevational view;

FIG. 3 is a plan view; and

FIG. 4 is an end elevational view thereof.

The appearance of the ends is identical and the appearance of the sides is identical.

I claim:

The ornamental design for a wall block, substantially as shown and described.
